UNITED STATES PATENT OFFICE.

JESSE G. ZIM, OF MEDFORD, MASSACHUSETTS, ASSIGNOR OF FIFTEEN PER CENT TO JOHN F. SHEEHAN, OF EVERETT, MASSACHUSETTS, FIFTEEN PER CENT TO WILLIAM C. GRAY, OF CAMBRIDGE, MASSACHUSETTS, FIFTEEN PER CENT TO LEON W. RICH, OF MEDFORD, MASSACHUSETTS, AND TEN PER CENT TO JOHN P. BUCKLEY, OF BOSTON, MASSACHUSETTS.

GALLEY LOCK.

Application filed April 28, 1928. Serial No. 273,447.

This invention relates to devices for clamping type upon a galley while proofs are being made and until the set-up is finally approved and ready to be assembled 5 in the chase.

Heretofore it has been common practice to place the type upon the supporting surface of the galley and clamp it in place by wedges inserted between the type and the 10 retaining wall upon the edge of the galley. Such practice has been objectionable the wedges tended to spread and distort opposite retaining walls which often permitted the type to become displaced to an undesirable extent. The insertion of such wedges wasted considerable of the printer's time and 15 very difficult to remove when it was desired to transfer the type set-up.

It is the object of the present invention to 20 provide a lock which may be employed conveniently to clamp the type upon the galley readily in a satisfactory manner without distorting any part of the galley and which may be used with set-ups of various sizes 25 and readily and conveniently removed without displacing the type when it is desired to transfer the set-up.

The invention will be more fully understood from the following description in conjunction with the accompanying drawings: 30 in which,

Fig. 1 is a plan view of a galley having assembled thereon a galley lock embodying the invention; and

Figs. 2 and 3 are sectional elevational 35 views taken upon the lines 2-2 and 3-3 respectively of Fig. 1.

Before explaining in detail the present invention, and the method or mode of operation embodied therein, it is to be understood 40 that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the claim 45 hereto appended or the requirements of the prior art.

A galley of the usual construction is illustrated in the drawings and comprises a bottom or type supporting surface 10 having a retaining wall 11 upon each of its longitudinal edges and a retaining wall 12 upon one of the end edges extending between the retaining walls 11. A galley lock embodying 55 the invention may comprise a cross member 14 and a longitudinal member 15 each of which are provided near one end with a shoulder 16 adapted to engage one side of the retaining wall. As illustrated, the shoulder 16 60 may be provided upon both the cross member 14 and longitudinal member 15 by forming a groove 17 in the bottom surface of each of these members, one side of which forms the shoulder 16.

Either or both of these members may be 65 adjusted to any desired position upon the galley and clamped in place to bring the shoulder 16 snugly against the retaining wall by any suitable clamp. In the form illustrated 70 the clamp may comprise a locking cam 20 pivotally mounted near one end of each member, as by a screw 21, and arranged so that one edge thereof may be moved against one side of the retaining wall and 75 thereby bring the shoulder 16 snugly against the other side of the wall to hold the members in any desired position.

A suitable arrangement may be provided 80 for locking the cross member and longitudinal member together in any desired relative positions. For this purpose, each of the members 14 and 15 may be provided with a longitudinal slot 22 and one member, such 85 for example as the cross member 14, may be 90 provided with a longitudinally extending opening 24 to receive the other member. A locking bolt 25 is positioned within the longitudinal slots 22 of each member and is provided with a head 26 at one end adapted 95 to engage the surface of one member and a clamping nut 27 upon the other end adapted to engage the surface of the other member thereby enabling said members to be clamped 100 together at any desired relative positions.

After type has been set up upon the supporting surface 10 of the galley, the cross member 14 is moved against the end of the set-up type and clamped upon the retaining wall 11. If the set-up type extends entirely 105 across the galley, the cross member 14 alone,

clamped upon the wall 11, is all that is necessary to retain the type in desired position. However, if the type does not extend entirely across the galley it is necessary to 5 employ the longitudinal member 15 which is inserted in the opening 24 of the cross member 14 and moved against the longitudinal edge of the set-up type and locked upon the retaining wall 12 by the clamp 20. The 10 cross member 14 and longitudinal member 15 are then clamped together by the clamping nut 27.

The galley lock of the invention is one which may be readily and conveniently assembled to hold the type in position upon the galley and may be detached just as readily and conveniently when it is desired to transfer the set-up type to a chase or the like. It will be noted that the galley lock 20 is so constructed that there is no tendency to spread the retaining walls of the galley thereby avoiding the resulting danger of displacing the set-up or imparting a permanent distortion to the retaining wall. This 25 is accomplished in the lock of the invention by the provision of a shoulder which is clamped against one side of the retaining

wall by a clamp mounted upon the lock and engaging the opposite side of the retaining wall. Furthermore it will be noted that the 30 galley lock of the invention may be readily adjusted to set-ups of various sizes.

What I claim is:

The combination with a galley having a type supporting surface and a plain retaining wall along its edge, of a galley lock comprising a longitudinal member and a cross member each having a slot terminating between its ends, a clamping bolt adjustably movable in said slots to clamp said members in a desired relation, and means for securing one end of each of said members to said retaining wall including a shoulder adapted to engage one side of said wall and a cooperating locking cam adapted to engage 45 the other side of said wall, said shoulders being constructed with a plane surface so that said members may be attached to and detached from said retaining wall as a unit by slipping said shoulders over the top of 50 the retaining wall.

In testimony whereof I affix my signature.

JESSE G. ZIM.
